UNITED STATES PATENT OFFICE.

JOHN KAUFMAN, OF HAZLETON, PENNSYLVANIA.

HEADLIGHT-OPERATING DEVICE.

No. 906,141.

Specification of Letters Patent.

Patented Dec. 8, 1908.

Application filed July 17, 1908. Serial No. 444,040.

To all whom it may concern:

Be it known that I, JOHN KAUFMAN, a citizen of the United States, residing at Hazleton, in the county of Luzerne and State 5 of Pennsylvania, have invented a new and useful Headlight-Operating Device, of which the following is a specification.

This invention relates to headlight operating devices adapted for use on locomotives 10 or motor railway cars.

The object of the invention is to provide an improved construction of such a device, reduce the number of moving parts to a minimum and thus simplify the entire mechanism. 15

The invention consists in general of a bracket arranged to be attached to the front of a car and carrying a sleeve or bearing, a shaft held within the bearing, a head light bracket pivotally supported at the outer end of the shaft, and the gearing connecting the sleeve or bearing with the head light bracket in such manner that as the car moves around a curve the head light will be thrown in 25 the direction of the movement.

The invention further consists in certain novel arrangement of details, and combinations of parts hereinafter fully described, illustrated in the accompanying drawings, 30 and specifically set forth in the claims.

In the accompanying drawings, like characters of reference indicate like parts in the several views, and; Figure 1 is a side elevation of the front of the car equipped with 35 this invention. Fig. 2 is a front elevation of the same, the full line showing the position on a straight track and the dotted line the position of the parts when the car is moving around a curve. Fig. 3 is a top plan 40 view, the full and dotted lines representing the full and dotted position of the parts as in Fig. 2. Fig. 4 is a vertical, longitudinal section showing the ball bearings.

The numeral 10 indicates the front of a 45 car whereon is mounted a bracket 11 having a sleeve or bearing 12 preferably formed integrally therewith and projecting horizontally from the bracket. This sleeve or bearing 12 has slot 13 in the lower or under part 50 thereof. Within the sleeve 12 is a shaft 14 having the outer end flattened as indicated at 15. Upon the flattened outer end of the shaft is carried a bracket 16, this bracket being provided with a segmental slot 17 to 55 admit the flattened pivot end of the shaft.

In order to pivotally mount the head

light bracket 16 on the flattened end 15 there is provided a pivot pin 18 passing through the bracket and the end of the shaft. The lower part of the sleeve or bearing 12 60 is provided at the end with a segmental gear 19 and the head light bracket is provided with a similar segmental gear 20 meshing with the gear 19. At 21 is shown a head light which may be of any desired 65 form or type and is secured to the head light bracket in any manner deemed suitable for the type of head light used.

Rigidly attached to the shaft 14 and passing through the slot 13 is a bar 22 at the 70 lower end of which is a weight 23 for the purpose of maintaining the bar in a vertical position without reference to the position of the car as it passes around a curve.

It is preferred that all of the parts be 75 arranged with ball bearings such as are shown as at 24 in Fig. 4. It is to be noted, however, that the type of ball bearings there shown is merely typical of such bearings and any other type that may be deemed advisable can be adopted.

In the operation of the device, as long as the car is traveling on a straight track the parts will be held in the position shown in Figs. 2 and 3 in full lines. This is due to 85 the fact that the weight 23 will hang vertically below the shaft 14 and thus prevent the rotation of that shaft and the consequent swinging of the head light bracket. Now let it be supposed that the car is trav- 90eling around a curve towards the right. It is a well known fact that on all railroad curves the outer rail is given what is known as super elevation. That is to say, the outer rail is elevated above the inner rail to a de- 95gree corresponding with the curvature and speed of the cars. As the car passes around the curve to the right, the upper end of the bracket 11 will be swung to the right and assume the position shown in the dotted lines 100 in Figs. 2 and 3. The result of this is, weight 23 remaining constantly in a vertical line below the shaft 14 said shaft will be rotated in the direction of a hand of a clock looked at from the rear. This will of course 105 rotate the head light bracket in the same way but since the bracket is geared by the gear 19 and 20 to the sleeve or bearing the bracket will not only be rotated in the same direction and maintain its perpendicular 110 but will be thrown into the position indicated by the dotted lines in Figs. 2 and 3,

or in other words the beam of the head light will be thrown to the right thus illuminating the track in the direction of travel of the car.

It will of course be understood that the super elevation of the outer rail of the track, over which a car carrying the device embodying my invention is traveling, at curves, must be of such degree as to overcome any centrifugal force, caused by the train rounding the curve, which would tend to throw the weight and its supporting arm out of perpendicular position.

It is obvious that the same effect will take place when the car turns to the left. The gears and weights are intended to be so proportioned with reference to the super elevation of the track on the various curves of the road that the beam of light from the head light will be thrown a proportionate amount to the right or left as the case may be no matter what the degree of curvature of the track may be. There has thus been provided a very simple device having but the two moving parts, that is the shaft and the head light bracket, which is efficient in operation and of great utility.

It is obvious that minor changes may be made in the form and proportions of the device to accommodate the various uses to which the same may be put and it is not therefore desired to confine the invention to the exact form and shape herein shown and described, but it is wished to include all which can properly come within the scope thereof.

Having thus described the invention, what is claimed as new, is;—

1. In a device of the kind described, a bearing bracket adapted to be attached to a car, a horizontal bearing held on said bracket provided with an arcuate slot in the lower part thereof, a shaft held in said bearing, a weighted arm attached to said shaft and passing through the slot, the head light bracket pivoted to the outer end of said shaft, and gears connecting the head light bracket and bearings.

2. In a device of the kind described, a bearing bracket adapted to be attached to a car, a horizontal bearing held on said bracket provided with an arcuate slot in the lower part thereof, a shaft held in said bearing, a weighted arm attached to said shaft and passing through the slot, a head light bracket

pivoted to the outer end of said shaft, a segmental gear on the front lower end of said bearing, and a second segmental gear formed on the lower end of said head light bracket meshing with the first gear. 55

3. In a device of the kind described, a bearing bracket adapted to be attached to a car, a horizontal bearing held on said bracket provided with an arcuate slot in the lower part thereof, a shaft held in said bearing provided with a flattened outer end, a counter weighted arm attached to said shaft and passing through the slot, a head light bracket segmental in plan provided with an arcuate slot adapted to receive the flattened end of the shaft, a pivot passing through the head light bracket and the shaft to rotatably attach the bracket to said shaft, and the gears connecting the head light bracket and the bearings. 60 65 70

4. In a device of the kind described, a bearing bracket adapted to be attached to a car, a horizontal bearing held on said bracket provided with an arcuate slot in the lower part thereof, a shaft held in said bearing provided with a flattened outer end, a weighted arm attached to said shaft and passing through the slot in the bearing, a head light bracket segmental in plan provided with an arcuate slot to receive the flattened end of the shaft, a pivot pin passing through the head light bracket and the flattened end of shaft to pivotally secure the head light bracket to the shaft, a segmental gear formed on the front lower portion of the bearing, a second segmental gear meshing with the first 80 85 90 formed on the lower portion of head light bracket.

5. In a device of the class described, a fixed member formed with a gear section, a member mounted to oscillate upon the said fixed member, a weight rigidly suspended from the oscillatory member, and a head-light support pivoted upon the said oscillatory member and formed with a gear section meshing with the gear section of the first 95 100 mentioned fixed member.

In testimony that I claim the foregoing as my own, I have hereto affixed my signature in the presence of two witnesses.

JOHN KAUFMAN.
